Attorney -

Patented Apr. 21, 1925.

UNITED STATES PATENT OFFICE.

CONRAD M. MEYER, OF SAN FRANCISCO, CALIFORNIA.

CONCENTRATOR.

Application filed September 2, 1924. Serial No. 735,458.

To all whom it may concern:

Be it known that I, CONRAD M. MEYER, a citizen of the United States, and a resident of San Francisco, county of San Francisco, 5 and State of California, have invented a new and useful Concentrator, of which the following is a specification.

The present invention relates to improvements in concentrators and has particular 10 reference to a stationary concentrator for separating metals from ore containing the same, or from mill tailings. It is particularly proposed to provide a grooved plate constructed in such a way as to automatically 15 effect a separation of the heavier mineral particles from ore or from mill tailings by passing the material mixed with water over the inclined surface of the plate and guiding the heavier particles into longitudinal 20 collecting channels, thence to a receptacle, and the lighter waste to the bottom of the plate, thence to a waste channel.

It is further proposed to utilize for this purpose intersecting diagonal grooves, preferably of approximately semi-circular cross-section in the top face of the plate, the grooves communicating at their lower ends with the channels referred to, and the delivering grooves being made slightly deeper 30 than the grooves traversing the same so that particles once caught in the delivering grooves follow the course of the same without being forced into a zigzag course.

It is further proposed to provide lateral 35 guards on either side of the grooved plate covering the channels previously referred to and controlling the intake area of the channels. As a further feature of my invention these guards are provided with hoods over 40 the discharge ends of the various grooves so as to enlarge the discharge area of the grooves into the channels and to furthermore produce slight eddy currents at the discharge end of the grooves whereby material of lighter weight is prevented from 45 entering the channels. Further objects and advantages of my device will appear as the specification proceeds.

The preferred form of my invention is 50 illustrated in the accompanying drawing, in which Figure 1 shows a top plan view of the same, Figure 2 a vertical longitudinal section through the same taken along the line II-II of Figure 1, Figure 3 a vertical transverse section taken along line III-III of 55 Figure 1, Figure 4 an end view of the de-

vice, and Figure 5 an enlarged detail view in plan of a small portion of the grooved plate. While I have shown only the preferred form of the invention, I wish to have 60 it understood that various changes or modifications may be made within the scope of the claims hereto attached without departing from the spirit of the invention.

My concentrator comprises a board 1 of 65 suitable dimensions which has inlaid therein a plate 2 of heavy glass or other hard material designed for long wear. The top face of the plate is provided with intersecting diagonal grooves 3 formed of approximately 70 semi-circular cross-section. Along the side edges of the grooved plate I provide collecting channels 4 into which the grooves discharge. The grooves are preferably made somewhat deeper at their discharge ends than at their upper ends, the increased depth preferably starting at the longitudinal center line of the board so that each lower end of each groove, counting 75 from the center line, is somewhat deeper than any one of the grooves crossing the same.

The object of this arrangement is to cause 80 heavier particles caught in the discharge ends of the grooves to follow the path of the same directly into the collecting channels without being diverted by the cross grooves and without being guided into a zigzag course that might deliver them at the bottom 85 of the board and not into the collecting channels.

The traversing grooves have the function 90 of increasing the actual concentrating area of the surface, and by causing repeated changes of direction of the flowing material in the grooves and frequent mingling of currents from opposite directions, to increase the opportunities for the material to be re-sorted and concentrated and for the heavy particles to work their way diagonally 95 toward the collecting channel and for the lighter waste to be washed down to the bottom of the plate into a waste channel.

The board as a whole may be made of any 100 suitable form, but I find that it is most advantageous to construct the board considerably narrower than is the adopted custom for rifle boards or concentrators of this character. On the sides of the board I provide flanges 6 which rise above the level of 105 the plate and which serve as support for the two guards 7 which are formed to in-

cline from the top of the flanges to the surface of the board so as to cover the collecting channels.

The guards prevent any material from entering the collecting channel except through the diagonal concentrate grooves. At the points where these grooves enter the collecting channel the guards are expanded into arches or hoods 8, enlarging the area through which concentrates and water may enter the collecting channels. These projecting hoods also serve the purpose of causing eddy currents in the medium flowing past the same whereby the lighter particles are deflected from the entrances into the collecting channels, while the heavier particles remain practically unaffected.

The guards are preferably made removable and are held in place by a plurality of spring clips 9 which may be engaged with the guards and the bottom of the board to effect a clamping action.

The two collecting channels discharge into a single transverse channel 10 from which latter the collected concentrates may be received in a suitable receptacle or may pass onto a second plate for further concentration.

In use the plate is supported on an incline by and suitable means (not shown in the drawing), and matter to be separated mixed with water is made to flow over the plate. The heavier particles naturally work their way to the bottom and are constantly re-mixed and re-sorted by passing over the grooves until the heaviest particles finally find their way into the somewhat deeper delivering grooves and are carried along to the end of the same and discharged into the collecting channels.

The slanting guards assist in smoothing the flow of the medium, and the small hoods

effect slight eddy currents at the bottom of the medium for diverting lighter materials from the collecting channels, while at the same time they allow heavier particles gathered in the delivering grooves to be freely discharged into the collecting channels. The guards can be easily removed for the purpose of inspecting and cleaning the collecting channels.

I claim:

1. In a concentrator of the character described, an inclined element having intersecting diagonal grooves with dished bottoms and steep remote edges in the top face thereof.

2. In a stationary concentrator of the character described, an inclined element having upon its top face two sets of parallel diagonal grooves crossing each other and each set discharging on opposite sides into a laterally placed collecting channel.

3. In a stationary concentrator of the character described, an inclined element having upon its top face two sets of parallel diagonal grooves crossing each other, each groove having a shallow section extending from the edge downwardly to the center and a deeper section extending from the center line downwardly and outwardly to the lateral discharge end.

4. In a concentrator of the character described, an inclined element having longitudinal collecting channels along the side edges thereof, diagonal grooves in the top face discharging into the said collecting channels and guards over the collecting channels controlling the intake area of the same with hoods formed in the guards over the grooves enlarging the discharge area thereof and causing eddy currents in a medium flowing over the inclined element.

CONRAD M. MEYER.
